[57] CLAIM

The ornamental design for an exit operator, as shown and described.

DESCRIPTION

FIG. 1 is a perspective view of an exit operator showing my new design;

FIG. 2 is a front view thereof;

FIG. 3 is a left side view thereof, the right side being a mirror image thereof;

FIG. 4 is a top view thereof;

FIG. 5 is a perspective view of a second embodiment of the design of FIG. 1, the only difference being the configuration of the cross bar;

FIG. 6 is a perspective view of a third embodiment of the design of FIG. 1, the only difference being the configuration of the cross bar;

FIG. 7 is a perspective view of a fourth embodiment of the design of FIG. 1, the only difference being the configuration of the cross bar;

FIG. 8 is an enlarged perspective view of the left mounting element shown separately for clarity of illustration;

FIG. 9 is a right side view of FIG. 8;

FIG. 10 is a front view of FIG. 8;

FIG. 11 is a left side view of FIG. 8;

FIG. 12 is a bottom view of FIG. 8;

FIG. 13 is a top view of FIG. 8;

FIG. 14 is an enlarged perspective view of the right mounting element shown separately for clarity of illustration;

FIG. 15 is a right side view of FIG. 14;

FIG. 16 is a front view of FIG. 14;

FIG. 17 is a left side view of FIG. 14;

FIG. 18 is a bottom view of FIG. 14; and,

FIG. 19 is a top view of FIG. 14.
